[57] CLAIM

The ornamental design for a cabinet, as shown and described.

DESCRIPTION

FIG. 1 is a front perspective view of a cabinet showing my new design;
 FIG. 2 is a side elevational view thereof; the opposite side elevational view being a mirror image;
 FIG. 3 is a front elevational view thereof;
 FIG. 4 is a top plan view thereof; and,
 FIG. 5 is an enlarged partial perspective view of the upper central portion of my new design shown in FIG. 1.
